UNITED STATES PATENT OFFICE

HUGH BURROUGHS BARBER, OF TOLEDO, OHIO, ASSIGNOR TO THE SURFACE COMBUSTION COMPANY, INC., OF TOLEDO, OHIO, A CORPORATION OF NEW YORK

BURNER

Application filed April 26, 1928. Serial No. 272,913.

This invention relates to improvements in gas burners and more particularly to a burner tip for burning mixtures of natural gas and air.

5 Burners which operate satisfactorily for burning mixtures of artificial gas and air do not necessarily operate satisfactorily for burning mixtures of natural gas and air. Natural gas has a much lower rate of flame 10 propagation than artificial gas and consequently tends to blow off at the tip under gas pressures which are materially lower than those which may be successfully used with artificial gas.

15 It is an object of this invention to provide a burner which shall permit mixtures of natural gas and air under relatively high pressure to be successfully burned without the flame blowing off.

20 In accordance with this invention I form a relatively deep well or tunnel in a body of a suitable heat resisting material and adjacent the bottom of the well I provide an abutment against which jets of a mixture of natural 25 gas and air impinge before emerging from the well, the feed ports through which the gas-air mixture enters the well being formed in the base of the burner.

For a more complete understanding of the 30 invention reference is made to the detailed description taken in connection with the accompanying drawing wherein Fig. 1 is a plan view of the burner and Fig. 2 is a cross section therethrough.

35 The material from which the burner tip is formed may be of any suitable heat resisting material such as lava and the burner may be considered as comprising a cylinder which is exteriorly threaded at one end to permit its 40 being screwed into a supply manifold or the like.

The burner is shown as a cylindrical body 10 and in this body is formed a cylindrical well or combustion tunnel 11 having a depth 45 which is preferably greater than its diameter. Adjacent the bottom of the well is formed an annular abutment or shoulder against which some of the feed ports discharge. The abutment preferably takes the form of an 50 undercut 12 having upwardly sloping walls.

Extending through the base 14 are two series of ports 16 and 18, these ports constituting the feed ports or passages through which the gaseous mixture is introduced into the well. The ports 16 have their axis inclined to the axis of the well in such a manner as to cause the gaseous mixture flowing through the individual ports 16 to impinge against the abutment formed by the undercut and be deflected towards the center of the well.

The angle included by the undercut is preferably a 45° angle and the angle of the inclination of each port 16 with respect to the axis of the well is preferably such that the axis of the port is not perpendicular to the upwardly sloping wall of the undercut but is oblique with respect thereto. Where the included angle of the undercut is 45° I prefer to incline each port 16 in such a manner that the angle included between the axis of the well and the axis of an individual port 16 is between 12° and 13°. This will cause the axis of the said port 16 to meet the sloping surface of the undercut at an angle of about 58°. The angle of impingement of the stream of gas may vary 75 within fairly wide limits without departing from the spirit of the invention, the angles given having been found most appropriate for a well having a ratio of depth to diameter as 4 to 3, or in other words where the depth of the well is somewhat greater than its diameter.

By causing some of the stream or jets of the incoming gaseous mixtures to impinge against the abutment, a violent swirling of the mixture is set up within the well with the result that the flame hugs the tip of the burner without any tendency to blow off even when the pressure of the mixture is relatively high. In actual practice I have found it possible to use pressures as high as 8½" of water without the slightest tendency of the flame to blow off.

Prior to my invention it has not been possible to burn perfect or self-sustaining mixtures of natural gas and air in relatively small burners of the tunnel or well type unless the pressure on the mixture was maintained relatively low. It will be understood that the gaseous mixture to be burned in

burners of the type disclosed in this application will be substantially perfect mixtures of natural gas and air or in other words such mixtures as will give complete combustion. Such mixtures are commonly known in the art as explosive gaseous mixtures.

5 What is claimed is:

1. A burner comprising a body having a well, means for introducing gas into the well 10 through the base of the body, an upwardly sloping undercut in the well wall, and means for directing jets of gas against the sloping wall of the undercut.

2. A burner comprising a body having a 15 round well of greater depth than diameter, means for introducing gas into the well through the base of the body, an upwardly sloping undercut in the well wall, and means for directing jets of gas against the sloping wall of the undercut.

3. A burner comprising a body having a 20 wall, means for introducing gas into the well through the base of the body, an upwardly sloping undercut in the well wall, a plurality 25 of gas ports in the base of the body discharging lengthwise of the well, and gas ports around the rim of the base discharging against the sloping wall of the undercut.

4. A burner comprising a body having a 30 well of greater depth than diameter, an upwardly sloping groove in the well wall at its foot, means for introducing gas into the well through the bottom thereof, and means for impinging streams of gas against the 35 sloping wall of the groove.

5. A burner comprising a body having a 40 well, means for introducing gas straightforwardly into the well from its bottom, and means for directing separate streams of the same gas around the bottom of the well toward the center of the well.

6. A burner comprising a body having a well, means for introducing gas straightforwardly into the well from its bottom, and 45 means for directing gas upwardly from the bottom of the well towards the center of the well.

7. A burner comprising a body having a 50 well of greater depth than diameter, an upwardly sloping undercut around the foot of the well wall, the included angle of the undercut being such that the sloping wall if projected would intersect the axis of the well at a point intermediate between the top 55 and bottom of the well, and gas ports discharging into the well through its bottom, some of said ports opening below said undercut.

8. A burner comprising a body having a 60 well of greater depth than diameter, an upwardly sloping undercut around the foot of the well wall, the included angle of the undercut being such that the sloping wall if projected would intersect the axis of the 65 well at a point approximately midway the

top and bottom of the well, and gas ports discharging into the well through its bottom, some of said ports opening below said undercut.

9. A gas burner comprising a body having a cylindrical well, an annular abutment 70 within the well, a plurality of feed ports opening into the well from the bottom thereof, some of said ports discharging against said abutment.

75 In testimony whereof I affix my signature.

CERTIFICATE OF CORRECTION.

Patent No. 1,769,821.

Granted July 1, 1930, to

HUGH BURROUGHS BARBER.

It is hereby certified that error appears in the printed specification of the above numbered patent requiring correction as follows: Page 2, line 22, claim 3, for the word "wall" read "well"; and that the said Letters Patent should be read with this correction therein that the same may conform to the record of the case in the Patent Office.

Signed and sealed this 5th day of August, A. D. 1930.

(Seal)

Wm. A. Kinnan,
Acting Commissioner of Patents.
